UNITED STATES PATENT OFFICE.

EARL R. BIGGS AND CARL R. BIGGS, OF CLINTON, INDIANA.

ELECTRIC-CIRCUIT SUPPORT.

Application filed January 22, 1923. Serial No. 614,145.

To all whom it may concern:

Be it known that we, EARL R. BIGGS and CARL R. BIGGS, citizens of the United States, residing at Clinton, in the county 5 of Vermilion and State of Indiana, have invented a new and useful Electric-Circuit Support, of which the following is a specification, reference being had to the accompanying drawings and to the letters and 10 figures of reference marked thereon.

This invention relates to means for supporting circuit wires used in electric systems, such as trolley wires, bonding wires used in connection with electric railway rails, 15 and electric cables, the invention having reference more particularly to means whereby electric circuit wires may be supported by metal beams having lateral base flanges, such as roof beams in mines where trolley 20 cars are used.

An object of the invention is to provide a strong and reliable electric-circuit support of such construction as to be adapted to be readily secured firmly to an over-head beam, 25 or to a railway rail, to reliably support an electric circuit wire and structurally secure the wire thereto.

Another object is to provide an improved electric-circuit support which shall be so 30 constructed as to be capable of being tightly clamped to various sizes of beams having base flanges, and which shall be adapted to be used for supporting a trolley wire insulated from the beams, or to support and 35 secure the bonding wire to afford reliable electric connections between two abutting rails or beams.

A further object is to provide an improved supporting hanger base which shall be 40 adapted to be readily secured adjustably and removably to a beam having base flanges, and suitable for use for various purposes, more particularly in supporting electric circuit wires in coal mines or in other mines, 45 and which shall not be costly to manufacture and shall be durable and economical in use.

With the above-mentioned and other objects in view, the invention consists in a 50 jaw-clamp of novel construction whereby to secure an electric circuit wire in place, being provided with means whereby to secure a circuit wire thereto; and, the invention consists also further in the parts and combinations and arrangements of parts 55 as hereinafter particularly described and

further defined in the claims appended hereto.

Referring to the drawings,—Figure 1 is a fragmentary perspective view of roof beams arranged as in coal mines and a 60 trolley wire provided with the improved support connected to one of the beams, Fig. 2 is a perspective view of the electric-circuit support base on an enlarged scale, 65 in connection with a beam or rail shown by broken lines; Fig. 3 is a vertical central section of the improved support attached to a beam shown in cross-section and supporting a trolley wire; Fig. 4 is a side view of a beam to which the electric-circuit support 70 is connected, the support being provided with a lateral brace; and, Fig. 5 is a fragmentary side view of a railway track provided with a bonding wire secured in place by means of the improved support. 75

Similar reference characters in the various figures of the drawings indicate corresponding elements or features of construction herein referred to in detail.

In mines, especially in coal mines, the 80 roofs of rooms and galleries are supported by means of metallic beams which in some cases are of I-section shape, but in many cases wornout or damaged railway rails are economically used as roof beams, each beam in 85 every case having a web 1 and two lateral base flanges 2 and 3. The roof beams extend transversely across the gallery or room and in many cases some of the beams are lower than the others, railway tracks are 90 laid longitudinally on the floor of the gallery or chamber, and a trolley wire is strung above the track and supported by the beams by more or less crude devices, resulting in 95 causing trouble in operation of the trolley cars used for hauling coal.

The improved support comprises a straight rod 4 having screw threads 5 extending from one end thereof on which a nut 6 is placed. The opposite end of the rod 100 has a jaw 7 fixed thereon adapted to engage the edge of one of the beam flanges, the jaw extending from one side of the rod and having a lip 8 thereon which has an inclined under face 9 adapted to engage the top of 105 the flange for support and clutching engagement when the rod is beneath the flange. The opposite side of the rod has a hanger - stud 10 fixed thereon of suitable length which has screw threads 11 thereon, the stud be- 110

ing fixed also to the jaw, and the stud preferably has a hole 12 therein to receive a bonding wire when required. The rod 4 has an adjustable jaw 13 thereon opposite to the fixed jaw 7 and it has a lip 14 provided with an inclined under face 15 adapted to engage the top of the opposite flange of the beam. The jaw 13 has a concave guide 16 adapted to engage the under side of the rod 4, the guide having sides 17 extending up to the bottom of the flange so as to operate in connection with the lip 14 to clutch tightly on the flange when forced by the nut 6.

15 Various types of clamps are secured to the trolley wire, and they may be adapted to be secured directly to the stud 10, with suitable insulating devices intervening; but preferably an insulator is used which comprises a shell 18 having a socket 19 provided with internal screw threads 20, the socket being directly connected to the stud 10, and the shell has an electrical insulator 21 therein in which a stud 22 is secured that 20 has screw threads 23. Preferably an extension rod 24 is provided which has a socket 25 to receive the stud 22, the socket having internal screw threads 26 to engage the screw threads 23, the rod having external screw threads 27 similar to the screw 30 threads 23. The extension rods may be made in different lengths, so that the trolley wire may be leveled when the bottoms of the roof beams are not all on one and the same level. The trolley wire clamp in the present case comprises a head 28 having a socket 29 to receive the end portion of the rod 24 and being provided with internal screw threads 30 to engage the screw 35 threads 27. The head 28 has a jaw 31 fixed thereon and a companion jaw 32 hinged to the head and provided with a clamp bolt 33, the trolley wire 34 being tightly secured between the jaws.

45 When there are curves or it is desired to laterally brace the supports an angle brace 35 is provided which has an eye 36 on one end that is connected to the extension rod 24, another base clamp is secured to the beam, and the brace is provided with an eye 37 connected to the stud 10, the eye being provided with a suitable insulator 38 suitably secured in place.

Obviously the extension rod 24 may be 55 transposed relatively to the insulator, the socket 25 being connected to the stud 10 and the socket 19 of the insulator connected to the end of the rod 24, the socket 29 then being connected to the stud 22 of the insulator.

60 In some cases the extension rod 24 is not required, the socket 29 in such cases being connected directly to the stud 22 and the socket 19 to the stud 10.

In Fig. 5 portions of two contiguous track 65 rails 39 and 40 are shown which are pro-

vided with splice bars 41 to constitute a rail joint, and a base clamp is secured to each rail, a bonding wire 42 being inserted in the holes 12 of the studs 10 and secured in place by means of a nut 43 on each stud. Thus the bonding wire is firmly connected electrically with the two rails, the rails being so connected by means of splice bars, the bars however being loose in many cases and failing to insure a reliable electric circuit.

In practical use the trolley wire is firmly supported by the devices described so as to be free from kinks or crooked portions, being level, or parallel to the plane of the railway track, so as to insure smooth operations of the trolley on the feed wire, the latter being laterally braced on curves when considerably below any beam by which the wire is supported. In case the track is removed from any portion of a mine the trolley wire and its supports may also be readily removed and saved for use elsewhere.

What is claimed as new is:—

1. An electric-circuit support including a rod having a jaw and a hanger stud fixed to opposite sides respectively of the rod, the rod having also another jaw adjustable thereon. 90
2. An electric-circuit support including a rod having a jaw and a hanger stud fixed to opposite sides respectively of the rod, the stud having a transverse hole adjacent to the rod, and a jaw adjustable on the rod. 95
3. An electric-circuit support including a rod having a jaw fixed on one side, and an insulator on the opposite side thereof, another jaw adjustable on the rod and provided with means to force it towards the fixed jaw, and a hanger clamp connected to the insulator. 100
4. An electric-circuit support including a rod having a jaw and a hanger stud fixed to opposite sides respectively of the rod, the rod having also another jaw adjustable thereon opposite to the fixed jaw, each jaw extending towards the other and having an under side extending at an acute angle from the rod. 110
5. An electric-circuit support including a rod having a jaw and a screw-threaded hanger stud fixed to opposite sides respectively of the rod, the stud having a transverse hole adjacent to the rod, another jaw adjustable on the rod and having a lip on one side and a guide on the opposite side thereof, and a device to be screwed onto the stud to secure a circuit wire thereto. 115
6. An electric-circuit support including a straight rod having a jaw and a screw-threaded hanger stud fixed to opposite sides respectively of the rod adjacent to one end thereof, the rod having screw threads extending from the opposite end thereof, an 120
7. An electric-circuit support including a straight rod having a jaw and a screw-threaded hanger stud fixed to opposite sides respectively of the rod adjacent to one end thereof, the rod having screw threads extending from the opposite end thereof, an 125
8. An electric-circuit support including a straight rod having a jaw and a screw-threaded hanger stud fixed to opposite sides respectively of the rod adjacent to one end thereof, the rod having screw threads extending from the opposite end thereof, an 130

other jaw adjustable on the rod, and a nut screwed onto the rod to force the jaws one towards the other.

7. An electric-circuit support comprising 5 a clamp rod having screw threads extending from one end and a jaw having a lip adjacent to the opposite end thereof fixed on one side of the rod, the opposite side of the rod having a screw-threaded stud thereon provided with a transverse hole adjacent to the rod, a nut on the clamp rod engaging the screw threads thereon, a jaw adjustable on the clamp rod and having a lip on one side and a guide on the opposite side thereof, and 15 a device to be screwed onto said stud to connect a circuit wire to the stud and thereby to said fixed jaw.

8. An electric-circuit support comprising a clamp rod having screw threads extending 20 from one end and a jaw having a lip adjacent to the opposite end thereof fixed on one side of the rod, the opposite side of the rod having a screw-threaded stud thereon, a nut on the clamp rod engaging the screw-threads thereon, a jaw adjustable on the clamp rod between the fixed jaw and the nut and having a lip thereon, an insulator connected to said stud, an extension rod connected to the insulator, a trolley wire 25 clamp connected to the extension rod, a base clamp having jaws and also a stud having an insulator thereon, and an angle brace connected to the extension rod and also to the insulator on said stud.

35 9. In an electric-circuit support, a base clamp comprising a rod having a jaw fixed on one side and a stud fixed on the opposite side thereof, the jaw having a lip on one side thereof extending partially over the rod, the stud having screw threads thereon to support a circuit wire, a jaw adjustable on the rod and having a lip on one side thereof extending partially over the rod, and means co-operating with the rod to force the 40 adjustable jaw towards the fixed jaw.

10. In an electric-circuit support, the combination with a trolley wire clamp, and an insulator to support the clamp, of a clamp rod having a stud fixed on one side thereof 50 to support the insulator, the rod having a jaw fixed on the opposite side thereof, the

jaw having a lip on one side thereof extending partially over the rod at a distance therefrom, a jaw adjustable on the clamp rod and having a lip on one side and a guide on the opposite side thereof, the lip extending partially over the rod at a distance therefrom and the guide having a concave face receiving a portion of the rod, and means co-operating with the clamp rod to force the 55 adjustable jaw towards the fixed jaw.

11. In an electric-circuit support, the combination of two clamp rods spaced apart in parallel arrangement, each of said rods having two jaws thereon of which one is fixed and the other adjustable on the rod and projecting from one side of the rod, one of the jaws having a screw-threaded hanger stud fixed thereto and extending from the opposite side of the clamp rod, an insulator 60 and an extension rod rigidly connected together and to one of said studs and having a trolley wire clamp secured thereto, and an angle brace connected to the remaining one of said studs and having operative connection 65 with the extension rod.

12. In an electric-circuit support, the combination with an electrical circuit wire, of a plurality of supports comprising each a clamp rod having two jaws thereon and 70 projecting from one side of the rod to co-operate one with another, one of the jaws having a screw-threaded hanger stud fixed thereto and projecting from the opposite side of the clamp rod, and a plurality of 75 devices co-operating with the hanger studs of the supports respectively to support the circuit wire.

13. In an electric-circuit support, a base clamp comprising a clamp rod having two 80 jaws thereon to co-operate one with another on one side of the rod, one of the jaws having a screw-threaded hanger stud fixed thereto and projecting beyond the opposite side of the clamp rod, and a screw-threaded 85 device to be screwed onto the hanger stud to connect a circuit wire substantially to the stud and thereby to the base clamp.

In testimony whereof, we affix our signatures on the 12th day of January, 1923.

EARL R. BIGGS.

CARL R. BIGGS.
